UNITED STATES PATENT OFFICE.

MIRABEAU N. LYNN AND ELMORE P. LYNN, OF RISING SUN, INDIANA,
ASSIGNORS TO THE LYNN ENGINE COMPANY, OF DAYTON, OHIO.

STEAM-ENGINE.

SPECIFICATION forming part of Letters Patent No. 377,463, dated February 7, 1888.

Application filed July 20, 1886. Renewed June 22, 1887. Serial No. 242,152. (No model.)

To all whom it may concern:

Be it known that we, MIRABEAU N. LYNN and ELMORE P. LYNN, both of Rising Sun, in the county of Ohio and State of Indiana, have 5 invented certain new and useful Improvements in Steam-Engines; and we do hereby declare the following to be a full, clear, and exact description of the same, reference being had to the accompanying drawings, forming a part 10 of this specification, and to the figures and letters of reference marked thereon.

In an application filed simultaneously herewith, and numbered 208,549, we have described and claimed an improved form and construction of engine wherein the inlet and exhaust ports and a valve co-operating therewith are located in the piston, the said valve mechanism being driven by the piston and moving in unison therewith, while the piston operates as 15 a cut-off to regulate the admission of steam to the cylinder; but as in said engine the movements of the valve to alternately open the exhaust and inlet ports take place at the termination of the stroke of the piston in opposite directions 20 as the crank passes the center, the valve cannot be given what is known as "lap and lead" without interfering with the action of the exhaust, for the reason that, the movement of the valve in opposite directions being equal, 25 the exhaust is closed as the inlet is opened, and vice versa, and if the inlet were opened in advance to take steam before the crank reached the center the exhaust would either remain open, permitting steam to blow through, or if 30 so placed as to close in advance it would be retarded in opening the exhaust at the opposite end of the stroke.

The object of our present invention is to provide such an engine as described in the 40 application referred to with a supplemental exhaust at or near the end of the stroke of the piston in one direction, whereby we are enabled to give the valve the necessary lap and lead to open the inlet before the piston has completed the back-stroke, and at the same time 45 provide an escape for steam in the cylinder during the interval between the closing of the inlet and opening of the direct exhaust at the end of the stroke in the opposite direction.

50 Our said invention consists, therefore, in the

novel combinations and arrangements of parts for effecting this result, as hereinafter more fully described, and pointed out in the claims.

In the accompanying drawings, Figure 1 is a longitudinal section of a cylinder, piston, 55 and valve mechanism, showing the application of our present invention. Fig. 2 is a longitudinal sectional view of said cylinder and piston, taken on a line at right angles to Fig. 1. Fig. 3 is a sectional view illustrating a modified form of valve. Fig. 4 is a view in perspective of our improved valve, the section being shown separated. Fig. 5 is a diagrammatic view showing the position of the inlet and exhaust ports near the termination of the 60 forward and return strokes of the piston.

Similar letters of reference in the several figures indicate the same parts.

As our invention relates solely to the construction and arrangement of the piston, cylinder, and valve mechanism of a direct-acting steam-engine, and is applicable to engines having two, three, or more cylinders, we have merely shown those parts of the engine deemed necessary to a full understanding of our present invention, it being understood that any approved form and construction of frame and other necessary parts and connections may be employed—such, for example, as shown in our before-mentioned application. 75

In the drawings, 1 is the cylinder, 2 the piston, and 3 the pitman connecting the piston and crank.

The cylinder 1 is furnished with a series of steam passages or ports, 4, leading from the 85 jacket or supply-pipe through the series and into the interior of the cylinder.

The piston 2, preferably of the trunk class, is provided midway of its ends with a steam-chamber, 5, which may be formed by reducing the piston at that point, the ends 6 7 of the piston, both above and below the said steam-chamber, being provided with packing-rings, thus forming practically a double piston. Within the piston is formed a transverse 90 valve-chamber, 8, in communication with steam-chamber 5, said valve-chamber being provided with inlet-ports 9 and exhaust-ports 10, opening through the wall of the valve-chamber and into the cylinder above the pis- 95 ton. 100

ton. Within this valve-chamber is located a reciprocating valve, 11, having ports 12, opening into the valve-chamber and co-operating with inlet-ports 9, and ports 13, co-operating with exhaust-ports 10 and opening into a passage or passages, 14, which latter communicate with an opening or openings, 15, in the lower head of the piston. The valve 11 may be either cylindrical, as shown in Fig. 1, or flat, as shown in Fig. 3; but the former is preferred. It is constructed in two sections, 16 and 17, each formed with a hollow cylindrical portion, 18, fitting the one within the other, and provided with packing-rings to prevent the passage of steam between them. The cylindrical portion 18 of the valve sections does not occupy the whole area of the proximate surfaces, sufficient space being left for the steam in the valve-chest to act upon the sections and force them apart and hold them firmly seated upon the valve-seats.

The outer end of the pitman 3 is screw-threaded or otherwise securely fastened to the upper section, 16, of the valve, as by a cross-piece, 19, in its cylindrical portion 18, so that the valve itself will form the pivot and point of attachment of the pitman and piston.

If it is deemed expedient to employ a flat-faced valve, the arrangement shown in Fig. 3 may be adopted; but in such case the pitman is to be pivoted directly in the piston, as at 20, while the valve is driven through a connection, 21, secured to the head of the pitman and pivoted in a block, 22, working in a guide, 23, in the upper section of the valve, this arrangement being substantially the same as is described in our before-mentioned application No. 208,549.

Referring to the valve shown in Fig. 1, it will be observed that it constitutes a practically-balanced valve, the overbalancing by the pressure of steam upon the proximate faces of the valve-sections being only sufficient to overcome the inertia of the parts and hold the sections pressed against their seats in the piston, and by attaching the pitman directly to the upper section of the valve the pressure of the piston and thrust of the crank are borne by said section, thereby relieving the lower section, which operates merely to permit the escape of steam from the valve-chamber through the opening in the piston in which the pitman works.

With the exception of the novel cylindrical balanced valve and the arrangement of the inlet and exhaust ports, the combination of devices as thus far described is arranged to operate substantially in the manner set forth in our application No. 208,549—that is to say, steam is admitted through passages 4 into the steam-chamber 5 between the ends of the double piston, from whence it passes through the valve-chamber and inlet-port into the cylinder above the piston. As the piston descends, the upper section or head closes the passages 4 in the cylinder, cutting off the supply of steam and permitting that contained in

the cylinder to act expansively. At the end of the stroke, and as the crank passes the center, the valve is shifted to open the exhaust 70 and close the inlet. Instead, however, of simultaneously opening the inlet and closing the exhaust as the crank crosses the center at the end of the back-stroke, we so arrange the valve with relation to the inlet and exhaust 75 ports that the exhaust-port shall close and the inlet begin to open just before the piston reaches the end of its back-stroke, and before the crank passes the center at the top. As the valve reciprocates in unison with the pitman, 80 its movement is reversed when the crank is at right angles, and it travels in the opposite direction during a half-revolution, and as this movement is the same, but in an opposite direction as that which effected the closing of 85 the exhaust and opening of the inlet-ports, it follows that the opening of the exhaust and closing of the inlet will take place at relatively the same point during the return movement of the piston—that is to say, the inlet-port 90 will not be closed nor the exhaust opened at the beginning of the back-stroke of the piston; but the closing of the one and the opening of the other will be delayed at the beginning of the back-stroke in the same degree that the 95 closing of the exhaust and opening of the inlet are advanced at the end of the back-stroke.

The supply of steam to the valve-chest having been interrupted by the closing of the ports 4 by the piston (or by the action of any 100 approved cut-off mechanism) near the end of the stroke of the piston, the steam contained in the valve-chest and cylinder acts expansively upon the piston, and inasmuch as the communication between the interior of the 105 cylinder and the valve-chest remains open and the exhaust-port closed at the beginning of the back-stroke, it becomes necessary to provide an auxiliary or supplemental exhaust to relieve the pressure in the cylinder and bridge 110 over the interval which elapses before the direct exhaust is opened. Otherwise the piston would be brought to a standstill. Such exhaust or relief is provided for in the following manner: Within the cylinder are formed a 115 series of ports or channels, 24, so located and arranged relative to the stroke of the piston that their upper ends shall be uncovered by the lower head of the piston just before it reaches the end of its stroke, thereby opening 120 a free passage for the escape of steam contained in the valve-chamber, as well as of so much of the steam in the cylinder as can escape through the inlet-port and before the direct exhaust opens.

By the employment of a supplemental exhaust of this character not only is the steam in the steam and valve chambers of the piston allowed to escape at each inward stroke of the piston, but it renders practicable the employment in the piston of a valve adjusted to have lap and lead, as before described.

What we claim as new is—

1. In a steam-engine such as described,

wherein steam is admitted and exhausted in the cylinder above the piston and through ports in the latter, and in combination with said cylinder and piston, a valve controlling the inlet and exhaust ports in the piston, a cut-off independent of said valve, and a supplemental or auxiliary exhaust, also independent of the valve, substantially as described.

2. In a steam - engine such as described, wherein the piston is provided with a steam-chamber intermediate its ends co-operating with steam-openings in the side of the cylinder, while the head of the piston serves as a cut-off, and in combination with said piston and cylinder, a reciprocating valve located in the piston and adjusted to have lap and lead with respect to the inlet and exhaust ports, and a supplemental or auxiliary exhaust-passage opened at or near the end of the stroke of the piston to relieve the pressure in the cylinder before the direct exhaust opens, substantially as described.

3. In combination with the cylinder and its steam - openings, the double piston having steam-chamber communicating with said openings in the cylinder, a cut-off for regulating the admission of steam to the said steam-chamber during the stroke of the piston, a valve carried by the piston and reciprocating in unison with its pitman to open and close the inlet and exhaust ports, and a supplemental or auxiliary exhaust independent of said valve and its exhaust-ports co-operating with the piston to relieve the pressure in the cylinder near the end of the stroke, substantially as described.

4. In an engine such as described, wherein steam is admitted through the side of the cylinder into a chamber in the piston and is conducted through inlet - openings into the cylinder above the piston, and in combination with said cylinder and piston, a cut-off, a reciprocating valve carried by the piston and connected to the pitman to vibrate in unison therewith, said valve being adjusted to open the inlet before the completion of the return or back stroke of the piston, a direct exhaust controlled by said valve, and a supplemental or auxiliary exhaust operating to relieve the pressure in the cylinder and steam-chamber before the completion of the stroke of the piston, substantially as and for the purpose set forth.

5. The combination, with the double piston having the steam-chamber and a reciprocating valve controlling the inlet and exhaust ports, said valve being adjusted to have lap and lead, of a cylinder provided with steam-ports and exhaust - passages at or near one end, one end of the said piston co-operating

with the steam-ports in the cylinder to cut off the supply of steam during the latter portion of the stroke, and the other end co-operating with the exhaust-passages to relieve the pressure in the cylinder at the end of the stroke, substantially as and for the purpose set forth.

6. In an engine such as described, and in combination with the piston and cylinder thereof, the cylindrical valve controlling the inlet and exhaust ports and located in the piston, said valve being constructed in two sections fitted to move the one upon the other, and the pitman secured directly to the upper section of said valve, substantially as described.

7. In combination with the cylinder and double piston having steam - chamber and cylindrical valve-chamber, the balanced cylindrical valve constructed in two sections moving one within the other, the upper section containing inlet and exhaust ports, being attached directly to the head of the pitman, substantially as described.

8. In combination with the cylinder having steam-ports in the side and supplemental exhaust-ports at or near the end, the double piston provided with the steam-chamber and valve-chamber, and the cylindrical valve made in two sections fitted to move one within the other, and the pitman secured directly to one of the sections of the valve, substantially as described.

9. In a steam - engine such as described, wherein steam is admitted and exhausted in the cylinder through a valve in the piston, and in which a cut-off is employed for limiting the admission of the steam to the valve-chamber, and in combination with said cylinder, piston, and valve, the latter driven from the pitman and adjusted to have lap and lead, the supplemental or auxiliary exhaust opened by the movement of the piston before the crank reaches the center, substantially as and for the purpose set forth.

10. In an engine such as described, and in combination with the piston thereof containing a valve-chamber, the cylindrical valve constructed in two sections, the outer section of said valve containing the inlet and exhaust ports and means whereby it can be firmly secured to the head of the pitman, and the inner section moving upon the other section and closing the opening for the pitman in the lower head of the piston, substantially as described.
